Dec. 1752

Oliver Pearl, of Lawrence, Mass.
Letters Patent No. 1752. Dated Apr. 28, 1863.

The Schedule referred to in these Letters Patent making part of the same.

To all whom it may concern:

Be it known that I, Oliver Pearl, of Lawrence, in the County of Essex and State of Massachusetts have invented or produced a new and original design for spinning flyers; and I do hereby declare that the following is a full and exact description of the same.

My improvement in the design or configuration of spinning flyers consists in the pyramidal form thereof, - that is to say - in the broad base A, and narrow top B, which gives a slope to the sides C.C. as represented in the drawing, making a part of this specification.

That I claim is the pyramidal form or outline of the flyer as herein described, and represented in the drawing.

Witnesses.
